FLATIRON AND OTHER HEATED APPARATUS

Jöhan Landberg, Alingsas, Sweden

Application May 11, 1935, Serial No. 21,027
In Sweden May 14, 1934

5 Claims. (Cl. 38—96)

The present invention relates to flat iron and other heated apparatus of the kind in which a body is heated by electricity, gas or otherwise and which after an extended period of heating can 5 reach such temperatures as are dangerous or harmful for surrounding objects which are combustible or otherwise sensitive to heat.

The invention has for its object to attach as an integral part of a flat iron a plurality of supporting legs which, by means of a manually operated device, are shiftable between supporting and inoperative positions. In the supporting position, the legs extend angularly from the flat iron and hold this at a safe distance from the 10 underlying material. In the inoperative position, the legs extend in mutually opposite directions at a reasonable distance above the heating body.

An especial advantage of the present invention 20 is to enable the operator by a simple pressure with a finger or preferably the thumb to rest the flat iron at maximum temperature at any place without endangering the underlying material.

The invention will now be described more 25 closely with reference to the accompanying drawings which illustrate by way of examples which are by no means limitative, a preferred manner of carrying out the invention.

Figure 1 is a side view of the flat iron with 30 the supporting legs of the device in inoperative position.

Figure 2 is a top view of the flat iron with the device as shown in Figure 1.

Figure 3 is an end view of the apparatus with 35 the heating body removed.

Figure 4 is a side view of the flat iron with the legs in supporting position.

Figure 5 is an end view of the iron with the device as shown in Figure 4.

40 Figures 6, 7 and 8 are details of a modified locking mechanism.

Figure 9 is a further modification of the locking mechanism.

The device consists of a heating body 20 and 45 a handle 22 connected thereto by a bracket 21. Between said bracket and the heating body a frame 4 is squeezed on which frame two pairs of supporting legs 1 and 2 are pivoted at 9 and 10 respectively. Each pair of legs is actuated by a 50 coil spring 15, according to Figure 2, which spring tends to shift the legs into supporting position shown in Figure 4.

The supporting legs are of such a length that 55 in their supporting positions, Figures 4 and 5, the underside of the heating body will be at a safe

distance from the underlying material or body 47, without the arrangement being unstable. The legs are further of such a shape that there is a considerable clearance between the heating body 20 and the legs 1, 2, in their supporting as well as in their inoperative positions. Practically, the only thermal communication between the legs and the heating body is thus through the pivots 9, 10 and the frame 4. The greatest part of the 10 insignificant heat thus communicated to the legs is radiated from the surface of the legs before reaching the support 47. In most cases it will therefore not be necessary to provide a heat insulation between the heating body 20 and the 15 frame 4. Furthermore, the legs can be made of any suitable material, such as metal.

In order to increase the surface of radiation of the legs in relation to their cross-sectional area, they can be made with a U-shaped cross-section.

The safety of this device is so great that the 20 apparatus may be left with the legs in supporting position for hours or days with the full heat on without danger.

The legs 1 and 2 are positively interconnected by means of a link 3 mounted on pivots 31, 32 25 and extending laterally to the handle.

The pivot 31 is provided on the leg 2 close to the pivot 10 whereas the pivot 32 is provided on a projection 33 extending from the leg 1 on the opposite side of the pivot 9. By this arrangement the legs can only be shifted simultaneously and in mutually opposite directions, as shown in Figures 1 and 4. On the frame 4 stop abutments 25 and 26 (see Figures 1 and 4) are disposed which abutments engage specially designed upper parts 30 34, 35 of the legs 1 and 2 when same are in their supporting position.

If an exterior force tends to displace the iron 40 forwards or backwards the one pair of legs will tend to shift to inoperative position on account of friction exerted by the support 47. This tendency is, however, entirely compensated by the fact, that the other pair of legs, which is positively connected with the first pair of legs is forced 45 to bear against its corresponding abutment and stay in position. The frame is integral with a projecting lug. A two-armed lever 6 is pivoted at a bolt 11 provided in the lug 5. The lower end of the lever is jointedly connected at 24 with the link 3. The upper end of the lever is provided 50 with a manually operable push member 8, preferably in the shape of a heat insulated button. Adjacent to the bolt 11, the lug 5 is provided with a conical stud 13 which is axially displaceable 55 between releasing and locking positions under the

action of a coil spring (not shown) provided inside a casing 14 mounted on the lug 5. The spring tends to hold the stud 13 in locking position. The upper arm of the lever 6 is provided with a slot 16 of such a shape that in the inoperative position of the legs, shown in Fig. 1, the slot will be engaged and locked by the stud 13. This is at its opposite end provided with a button 12 which, if pushed, shifts the stud to its releasing position in which the lever 6 is free to move out of the position shown in Figure 1.

The apparatus operates in the following manner:

When the operator wants to rest the iron, the button 12 is pushed in which releases the lever 6, the link 3, and the legs 1, 2. The springs 15 then shift the legs automatically into supporting positions in which the parts 34, 35 engage the stop abutments 25, 26. The heating body 20 is then held at a safe distance from the underlying material or body. It should be noted that the legs in their supporting positions, according to Figure 4, are slightly oblique. The object thereof is to make the horizontal projections of the pivots 9, 10 to fall inside a polygon, the corners of which are formed by the supporting points 36 to 39.

If the arrangement of the device is such that the pivots 9, 10 fall outside the polygon defined by the supporting points 36 to 39, the weight of the apparatus will tend to tip the legs into inoperative position so that the hot iron will come into contact with the underlying material and thus do harm.

When the operator wants to use the iron again he presses the pushing member 8 forward in the direction of the arrow in Figure 4 against the action of the springs 15. Simultaneously, the two-armed lever 6 moves the link 3 backwards, so that the legs 1, 2, moving in mutually opposite directions, shift to their inoperative positions in which they cross each other and remain parallel to the flat side of the iron as is shown in Figures 1 and 2.

At the same time the slot 16 engages the conical stud 13 and moves this first from its locking position and then, when the lever 6 has reached its final position corresponding to the inoperative position of the legs, a wider portion of the slot 16 will allow the stud 13 to fall back into its locking position under the action of the spring in the casing 14. In this position the lever 6, the link 3, and the legs 1, 2 are locked in their inoperative positions.

When the supporting legs are raised to their inoperative position, they are entirely out of the way and do not, in any way, hinder the operator, or obstruct his view of the flat iron in guiding the same over the work.

In Figures 6, 7 and 8 the locking device is slightly modified. The two-armed lever 6 in Figure 1 is here substituted by a corresponding lever 40 having an aperture 19 instead of the slot 16. The lug 5 of Figure 1 corresponds here to the lug 41. This is provided with a hole in which a ball 17 is accommodated. The ball is actuated by a leaf spring 18 mounted on the lug 41 and tending to push the ball into locking position in relation to the hole 19. The leaf spring may be substituted by a coil spring of equivalent action. When the legs are shifted from their supporting to their inoperative positions the lever 40 swings from the position shown in Figure 8 to its vertical position indicated from the opposite side in Figure 6. At the end of this shifting movement the ball 17 slides into the hole 19 and locks the lever 40,

the link 3, and the legs 1, 2 against the action of the springs 15.

In the embodiment of the locking device shown in Figure 9 the lug 5 is substituted by a lug 42 provided with a hook 43 guiding a spring 27. At the one end this is fastened at 7 and at the other end is bent like a knee 23, 46. This knee bears against a stud 44 projecting from a lever 45 corresponding to the lever 6 in Figure 1.

The operation of the device according to the embodiment shown in Figure 9 is as follows: In this figure the parts take up positions corresponding to the supporting positions of the legs. During the shifting movement of the legs from their supporting to their inoperative positions, the lever 45 is rotated in a clock-wise direction so that during a first period the upperside of the stud 44 bears against and slides on the spring portion 23. During this interval the spring power tends to restore the lever 45, the link 3, and the legs 1, 2 to their supporting positions. During a second period, after the stud 44 has passed the point of the knee 23, 46, the underside of the stud 44 bears against and slides on the spring portion 46. During this second period the spring action tends to shift the lever 45, the link 3, and the legs 1, 2 to their inoperative positions.

Provided the spring 27, 23, 46 has a sufficient power the springs 15 in Figure 2 may be omitted and the legs tend always to take up either their inoperative or supporting positions. In this modification the button 12 and the locking devices of Figures 1 to 8 are also superfluous.

The above described devices while extremely simple and of reasonable cost to manufacture can be very easily applied to, and removed from any flat iron of common type.

Having now particularly described and ascertained the nature of my said invention and in what manner the same is to be performed, I declare that what I claim is:—

1. A flat iron comprising a handle, a heated body, a bracket uniting the handle with the body, pairs of supporting legs pivoted on the bracket and shiftable between supporting and inoperative positions, a link jointedly and positively connected with said supporting legs on reverse sides of their pivots to ensure a shifting movement of the pairs of legs in mutually opposite directions, a manually operable push member actuating said link to shift the legs and spring-actuated locking means cooperating with said member to retain the same and the legs in one of their shifting positions.

2. A flat iron comprising a handle, a heated body, a bracket uniting the handle with the body, pairs of supporting legs pivoted on the bracket and shiftable between supporting and inoperative positions, a link jointedly and positively connected with said supporting legs on reversed sides of their pivots to ensure a shifting movement of the pairs of legs in mutually opposite directions, a two-armed manually operable push lever pivoted on a part rigidly connected with said bracket and jointedly connected to said link with which to shift the legs and spring actuated locking means cooperating with said lever to retain the same and the legs in one of their shifting positions.

3. A flat iron comprising a handle, a heated body, a bracket uniting the handle with the body, pairs of supporting legs pivoted on the bracket and shiftable between supporting and inoperative positions, a link jointedly and positively connected with said supporting legs on reverse sides of

their pivots to ensure a shifting movement of the pairs of legs in mutually opposite directions, a two-armed manually operable push lever pivoted on a part rigidly connected with said bracket and jointedly connected with said link to shift the legs, a spring actuated locking stud co-operating with said lever to retain this and the legs in one of their shifting positions.

4. A flat iron comprising a handle, a heated body, a bracket uniting the handle with the body, pairs of supporting legs pivoted on the bracket and shiftable between supporting and inoperative positions, a link jointedly and positively connected with said supporting legs on reverse sides of their pivots to ensure a shifting movement of the pairs of legs in mutually opposite directions, a two-armed manually operable push lever pivoted on a part rigidly connected with said bracket and jointedly connected with said link to shift the

legs, and a spring actuated ball detent co-operating with said lever to retain this and the legs in one of their shifting positions.

5. A flat iron comprising a handle, a heated body, a bracket uniting the handle with the body, pairs of supporting legs pivoted on the bracket and shiftable between supporting and inoperative positions, a link jointedly and positively connected with said supporting legs on reverse sides of their pivots to ensure a shifting movement of the pairs of legs in mutually opposite directions, a two-armed manually operable push lever pivoted on a part rigidly connected with said bracket and jointedly connected with said link to shift the legs, and a resilient knee co-operating with an abutment of said lever to hold this and the legs in the one and in the other of their shifted positions.

JÖHAN LANDBERG.
